(57) **CLAIM**

I claim the ornamental design for an instrument panel for automobile digital audio disk player and navigation system, as shown and described.

DESCRIPTION

FIG. 1 is a top perspective view of an instrument panel for automobile digital audio disk player and navigation system of the present invention;

FIG. 2 is a front view thereof;

FIG. 3 is a first side view thereof;

FIG. 4 is a second side view thereof;

FIG. 5 is a top view thereof;

FIG. 6 is a bottom view thereof;

FIG. 7 is a rear view thereof; and,

FIG. 8 is a top perspective view thereof, wherein the panel portion is in the open position.

The broken lines shown in the drawings form no part of the claimed design.
